UNITED STATES PATENT OFFICE.

MAURICE J. ROSS AND NEWTON B. WACHHORST, OF SAN FRANCISCO,
CALIFORNIA.

CAN-BODY-FORMING MACHINE.

SPECIFICATION forming part of Letters Patent No. 716,111, dated December 16, 1902.

Application filed February 25, 1902. Serial No. 95,604. (No model.)

To all whom it may concern:

Be it known that we, MAURICE J. ROSS and NEWTON B. WACHHORST, citizens of the United States, residing at San Francisco, in the county of San Francisco and State of California, have invented certain new and useful Improvements in Can-Body-Forming Machines, of which the following is a specification.

Our invention relates to improvements in machines for making can-bodies, the object of our invention being to provide a machine of this character which shall be simple in construction and of great capacity for the size of the machine.

Our invention therefore resides in the novel construction, combination, and arrangement of parts for the above ends hereinafter fully specified, and particularly pointed out in the claims.

In the accompanying drawings, Figure 1 is a front elevation of our improved machine, certain parts being broken away. Fig. 2 is a side view of the same, partly in section, on the line A A of Fig. 1. Fig. 3 is a horizontal section on the line B B of Fig. 2. Fig. 4 is a vertical section on the line C C of Fig. 2. Fig. 5 is a vertical section on the line D D of Fig. 3 looking in the direction of the arrow d. Fig. 6 is a similar section on the line E E of Fig. 3 looking in the direction of the arrow e. Fig. 7 is a section on the line F F of Fig. 2 looking in the direction of the arrow f. Fig. 8 is a detail plan view of the device for regulating the gage. Fig. 9 is a cross-section of the same. Fig. 10 is an enlarged view of a portion of the horn, showing the edges of the can in position thereon. Fig. 11 is a detail perspective view of the flat can-body blank. Fig. 12 is a side elevation of the expandible horn. Fig. 13 is a detail side view of the pin for expanding the same. Fig. 14 is a detail cross-section of the horn.

Referring to the drawings, 1 represents a suitable base, upon the rear side of which is mounted a standard 2, supporting at its upper end a bearing 3 for a shaft 4. Upon the front end of said shaft is secured a carrier-disk 5, having thereon the horns or mandrels 6 for shaping and sizing the flat sheet-metal bodies into the can-bodies. Upon the rear

end of said shaft is fixedly secured a ratchet-wheel 7, having ratchet-teeth 8, and behind said ratchet-wheel, upon the shaft 4, is loosely mounted a driving-lever 9, having pivoted thereon a pawl 10, pressed upwardly by a spring 11 into engagement successively with the ratchet-teeth 8. The lever 9 is oscillated by means of a link 12, attached by a crank-pin 13 to a disk 14 on a shaft 15. Said shaft 15 rotates at its rear end in a bearing 16, supported upon a standard 17 upon the base-plate 1, and at its front end in a bearing 18 upon a standard 19 upon said base-plate, said shaft 15 carrying at its front end a pulley 20 for deriving power from any suitable source. By this means the disk 5, carrying the horns or mandrels 6, is given an intermittent rotation, and there being eight ratchet-teeth in the ratchet-wheel and eight horns or mandrels upon said disk the disk moves through one-eighth of a revolution at a time, and by said movements carries said horns in succession to the points at which the several operations are performed on the can-body blank.

Upon the standard 19 is supported a table 21, through an opening 22 in which the mandrels 6 are carried in succession by the revolving carrier-disk. Said table has on each side of said opening removable sections 23, so secured thereto as to leave on each side a recess 24, in which are received shapers 25, pressed outward by means of springs 26. The outer edges of said shapers are rounded, as shown, as likewise are the edges of the table above and below said shapers.

Above the table are secured gages 27, adjustable on said table by means of screws 28, working in slots 29 in said gages, said slots having beveled sides, as shown in figure, so that the edges of said gages on opposite sides of the opening can be moved nearer to or farther from each other, as may be desired, according to the size of the can-body blank. Said blanks 30 are fed into the space between said gages either by hand or by suitable mechanical means, and before being so fed they have their opposite edges bent or folded away from each other, as shown at 31 32 in Fig. 11. Over said flat blank as it lies between said gages move the slides 33, which slide in guide-

ways 34 on the table to and from the opening 22 and carry pusher-plates 35 36. Said slides have downward extensions or lugs 37, to which are attached links 38, jointed at the other ends 5 to levers 39, pivoted on a pin 40, secured in the bottom of a hanger 41, extending downward from the table. The lower ends of said levers 39 carry cam-rollers 42, which move in cam-grooves 43 in disks 44, secured upon the 10 shaft 15. Thus at predetermined times in the revolution of said shaft first the horn or mandrel descends down onto the middle of the flat blank 30 and carries the same into the opening 22, forming it into a U shape, and then 15 the pusher-plates 35 36 advance against the upstanding sides of the U-shaped blank and force the same toward each other around the horn or mandrel, so that the folded edge 31 of the can-body blank on one side passes over 20 and hooks on to the folded edge 32 on the other side.

To limit the movement of the edge 32, moved into position by the pusher-plate 36, we provide a gage 45, which consists of a narrow plate working in a radial slot in the horn and pressed outward by means of springs 46. This gage will normally extend from the periphery of the horn and will arrest the movement of the edge 32 of the flat can-body. During 25 the whole of this time the horn will have been collapsed. For the purpose of properly shaping the can-body and also to bring the hooked edges together and to accurately size the can-body we make said horns expansible. Expansible horns for this purpose are old and well known, and we do not use herein any novel construction for this purpose. Said horn comprises two sections 47 48, jointed together, as shown at 49, and normally drawn 30 together by a spring 50. A pin 51 passes into the center of the main section 47 and has cut into the side thereof two depressions 52. In the smaller section 48 there are screwed two screws 53, the ends of said screws abutting 35 against the round or butt side of the pin 51 when the pin is wholly pushed inward, thereby holding said outer section out against the action of said spring 50. When the pin is drawn out, the two depressions 52 come opposite to the ends of the screws 53 and the screws move thereto under the action of said spring, thereby causing the horn to collapse. In order to expand the horn at the proper time, we provide a circular cam-rail 55, having 40 its upper end 56 beveled away from the carrier-disk at the top, so that when the head 57 of each pin in succession is brought into contact with said cam-rail it will be pushed inward, thereby expanding said disk. As said 45 head travels along the edge of said cam-rail through about one-quarter of a revolution of the carrier-disk it will be held in and the horn will be kept expanded until said head reaches a T-slot 58, which is in the line of the circular rail. Into said T-slot said head will enter, the outer lips 59 of said T-slot converging inwardly as the head advances, as shown

in detail in Fig. 4, so that as said head moves along in said T-slot the pin 51 is drawn outward, thereby shifting the depressions so that 50 they register with the screws and the outer section collapses onto the main section under the action of the spring. Before this takes place, however, it is necessary to close the seam of the can-body. For this purpose there 55 are provided two standards 61 62, having formed therein vertical guideways 63, in which move slides 64, carrying upper and lower rollers 65 66. Through vertical slots 67 in said slides extend from the rear sides of 60 said guideways pivot-pins 68, on which are vertically mounted cams 69, to which is pivotally connected a bar 70. The end of said bar is jointed to a link 71, connected to a lever 72, pivoted on a standard 73, the upper 65 end of said lever 72 carrying a cam-roller 74, working in a cam-groove 75 in a disk 77, mounted on the cam-shaft. By this means in the revolution of the cam-shaft the slides will be raised. Said slides carry, the one in front 70 of the horn, a thrust-block 80, adjustable in an extension from said slide, and the other, in the rear of the horn, a guideway 81 for a bumper. Said bumper 82 is formed with beveled edges, sliding in said guideway and is 75 jointed, as shown at 83, to a link 84, slotted, as shown at 85, to pass around the cam-shaft and also to guide it on said cam-shaft, said link having on its rear end a roller 86, rolling in a cam-groove 87 in a disk 88 on the cam-shaft. By this construction after the thrust-block and the bumper-guide have been raised to the proper position the bumper is moved forward by the revolution of the cam-shaft, and the end of said bumper presses against 80 the seam and closes the same down upon the horn. By the continued revolution of the cam-shaft the bumper is withdrawn, the slides are lowered, and the pawl engages the next 85 ratchet of the ratchet-wheel and advances the disk carrying the horns thereon one-eighth of a revolution. The can-bodies thus formed can be removed from the horns at any time between the operation of seaming and the operation of placing the body upon the horn 90 either by hand or by mechanical means, as may be desired.

An important advantage arising from the construction of our machine is that we are enabled to perform the two operations of placing the can-body blank upon the horn and bumping the same to close the seam at the same time on two bodies, this being due to the fact that the body is moved from one position after it has been placed upon the horn 95 into another position for bumping. In prior machines for forming can-bodies it has been customary to perform the operations of forming the can-body and bumping the same while the can-body remains in the same position. 100 We obtain an important advantage by moving the can-body into another position after forming and before closing the seam, thus 105 gaining time.

We claim—

1. A can-body-forming machine comprising a disk, horns or mandrels carried thereon, a table provided with means for holding a flat can-body blank in the path of the horns, means for intermittently rotating said disk to press a horn upon said blank to bend the same, pusher-plates at the sides of the blank, means for pushing said plates toward each other to bring the edges of the blank together and form the seam, and a bumper to which said horn is brought by its revolution with the disk, said bumper being provided with means for pressing the body to close the seam, substantially as described.

2. In a can-body-forming machine, the combination of a disk, a series of horns or mandrels carried thereon, a table having an opening therethrough interposed in the path of the horns, adjustable gages for adjusting the position of a flat can-body blank in said opening, pusher-plates at the sides of said opening, means for pushing said plates toward each other to push the edges of the blank into position, a thrust-block and a bumper, means for raising said thrust-block and bumper into position before and behind a horn respectively, and means for moving said bumper against the can-body on the horn to close the seam, substantially as described.

3. In a can-forming machine, the combination of a disk, means for intermittently rotating the same, a series of horns carried on said disk, a table having an opening through which the horns are carried in succession by the revolving disk, shapers for bending the flat can-body blank, having rounded edges and resiliently supported in said table on each side of said opening means for bringing the edges of the flat blank together to form a seam and means for closing said seam, substantially as described.

4. In a can-body-forming machine, the combination of a revolving disk, horns or mandrels carried thereon, a table having an opening through which the horns pass in succession, shapers on each side of said opening for bending a can-body blank around the horn, means for closing the edges of the blank to form a seam and means for closing said seam, substantially as described.

5. In a can-body-forming machine, the combination of a table having an opening, means for passing a series of horns in succession through said opening, shapers on each side of said opening for bending a can-body blank around a horn, means for pressing the edges of the blank together to form a seam, and means for closing said seam, substantially as described.

6. In a can-body-forming machine, the combination of a table having an opening, a series of horns, means for passing said horns in succession through said opening, shapers at the sides of said opening for bending a can-body blank around a horn, pusher-plates at the sides of said opening for pushing the edges

of the blank together to form a seam, and means for closing said seam, substantially as described.

7. In a can-body-forming machine, the combination of a table having an opening, a series of horns, means for passing said horns in succession through said opening, means for bending a can-body blank supported in said opening around a horn as it passes therethrough, means for bringing the edges of said blank together to form a seam, a thrust-block and a bumper, means for transporting the horn with the can-body thereon into position between said thrust-block and bumper, and means for pressing said bumper against the seam to close the same, substantially as described.

8. In a can-body-forming machine, the combination of a table having an opening, means for supporting a flat can-body blank across said opening, a series of horns, means for passing said horns in succession through said opening, means for bending a can-body blank around a horn as it passes through said opening, means for closing the edges of said can-body, means for transporting said blank to a distance from said opening, a thrust-block and a bumper, means for moving said thrust-block and bumper to opposite sides of said can-body, and means for drawing said thrust-block and bumper together on opposite sides of the can-body to close the seam, substantially as described.

9. In a can-body-forming machine, the combination of a table having an opening, means for supporting a flat can-body blank in said opening, a series of horns, each horn being provided with a gage extending above the rounded surface of said horn, and a spring for pressing outward said gage, means for passing said horns in succession through said opening, means for bending said blank around a horn when so passing, a pusher-plate on one side of said opening arranged to engage the edge of the blank and to press the same against said gage, means for pressing the other edge in engagement with the first edge, means for removing said horn with the can-body thereon from said opening, and means for closing the seam, substantially as described.

10. In a can-body-forming machine, the combination of an expansible horn having a pin the movement of which expands the same or permits it to collapse, a disk upon which said horn is carried, means for rotating said disk, means for supporting a can-body blank in the path of the horn, means for bending the blank around the horn, a device automatically engaging the pin as the horn moves to shift said pin to expand the horn before the blank is bent around the same, said device being also provided with means for shifting the pin to permit the horn to collapse, after the can-body has been formed around the horn, substantially as described.

11. In a can-body-forming machine, the

combination of a disk, means for rotating the same, a series of horns carried by said disk, each horn being expansible and having a pin the reciprocating movement of which expands
5 the horn or permits it to collapse, a cam-rail engaging said pin to shift the same to expand the horn, means for exposing a can-body blank in the path of the horn, means for bending said blank around the horn in its passage,
10 means for closing together the edges of said blank, said rail also having at the end thereof an extension engaging the pin to shift the same to permit the horn to collapse, substantially as described.
15 12. In a can-body-forming machine, the combination of a disk, means for rotating the same, a series of horns carried by said disk, each horn being expansible and having a pin the reciprocating movement of which expands

the horn or permits it to collapse, a cam-rail 20 engaging said pin to shift the same to expand the horn, means for exposing a can-body blank in the path of the horn, means for bending said blank around the horn in its passage, and means for closing together the edges of 25 said blank, said rail having at the end thereof a T-slot arranged to engage the head of the pin to shift the same to permit the horn to collapse, substantially as described.

In witness whereof we have hereunto set our 30 hands in the presence of two subscribing witnesses.
